UNITED STATES PATENT OFFICE

ALBERT H. NEE, OF BOZEMAN, MONTANA

LUMBERMAN'S TOOL

Application filed February 26, 1929. Serial No. 342,831.

This invention relates to tools and more particularly to a compound tool for use by lumbermen and including an axe head and handle which has associated therewith means 5 for measuring a log and determining the board feet of lumber in the log.

One object of the invention is to provide a tool of this character which may be used for chopping purposes and which also has a 10 marker by means of which the private mark of a lumber company may be applied to logs so that the logs may be identified.

Another object of the invention is to provide a tool of this character having scale 15 markings upon its handle and an abutment at the forward end of the handle so that by extending the handle across one end of a log the diameter of the log may be ascertained and through the medium of a scale upon the 20 handle the board feet of lumber in the log determined.

Another object of the invention is to provide the handle with a rod slidably received therein which may be extended when measuring 25 a log of greater diameter than the length of the handle and to further provide improved means for releasably securing the rod in either an extended or retracted position.

The invention is illustrated in the accompanying drawing, wherein

Fig. 1 is a perspective view showing the axe applied to a log in order to measure the diameter of the log,

Fig. 2 is an enlarged view showing the tool 35 in side elevation with the rod extended,

Fig. 3 is a view taken at right angles to the view shown in Fig. 2 with a portion of the handle shown in section, and

Fig. 4 is a view looking at the rear end of 40 the handle, the dotted lines indicating the position assumed by the latch when swung out of operative engagement with the extension rod.

The log shown in Fig. 1 and indicated by 45 the numeral 1 represents a log of any desired length and diameter. In this view the tool has been shown applied to one end of the log in order to ascertain its diameter, and it will be noted that this tool includes an axe head 2 and a handle 3, one end of which is received

in the eye of the axe head. This axe head includes the usual cutting blade 4 and striking end 5 but the striking end is formed with raised characters, as shown at 6 in Fig. 1, so that, when a log is struck with this end of the head 2, characters corresponding to those provided upon the striking end of the axe head will be formed in the log and thereby identify it.

The handle which is preferably formed of wood carries at its forward end a strip 7 which is pivoted thereto through the medium of a screw or similar fastener 8 so that it may be turned from an inoperative position in which it extends longitudinally of the head to an operative position. When in the operative position, the strip projects from opposite sides of the head, as shown in Figs. 1 and 3, and will engage the log so that the tool may be easily applied with its handle extending across the end of the log. Inch markings are formed upon the handle, as shown at 9 in Fig. 3, and in cooperating relation to the inch markings is provided a lumber scale 10 shown in Fig. 2. There has also been provided the numerals 12, 14 and 16, as shown at 11, which designate the length of a log and if a log being measured is sixteen feet in length the number of board feet in the log may be readily ascertained by obtaining its diameter through the medium of the inch markings 9 and then reading the number upon the scale 10 opposite the numeral 16 and above the numeral which designates the diameter of the log.

In some cases the log to be measured will be of greater diameter than the length of the axe handle, and in order to allow a large log to be easily measured, there has been provided an extension rod 12 having scale and inch markings thereon, as shown, respectively, in Figs. 2 and 3. This rod which is rectangular in cross section, as shown in Fig. 4, is slidably received in a bore 13 formed axially of the handle and, therefore, the rod may be slid longitudinally into and out of the pocket but will be prevented from turning therein. Grooves are formed circumferentially of the rod adjacent its inner and outer ends to provide annular seats 14 and 15, and in order to

releasably secure the rod in either a retracted or extended position, there has been provided a latch 16 which consists of a metal plate pivotally connected with the rear end face of the handle by means of a screw 17. This latch is formed with a recess 18 leading from one side so that the latch may be swung into place about the rod with portions of the latch bordering the recess engaged in one of the seats 10 and adjacent its free end the latch is formed with a second recess 19 to receive a screw 20. When the latch is engaged with the screw 20, the head of this screw has frictional engagement with the outer surface of the latch and 15 will serve to retain the latch in its operative position and, therefore, the rod may be securely but releasably held in either a retracted or extended position.

The blade 4 functions as a flat head to rest 20 against the end of a log or other surface to prevent turning of the handle when the device is positioned for ascertaining measurements. The element 7 constitutes a stop to engage a side of the log or other object and 25 limits the movement of the device in one direction. The scale markings may consist of any desired calibrations, depending upon the specific use for which the device is designed.

Having thus described the invention, I 30 claim:

A lumberman's tool comprising an outer member provided with a longitudinal bore, an inner member slideable in the longitudinal bore of the outer member, both members being provided with scale calibrations, and the inner member having circumscribing grooves at different points in its length, a flat head and pivoted stop at one end of the outer member to properly position the tool, a headed 40 element at the opposite end of the outer member to one side of the longitudinal bore, and a latch pivoted to the outer member at the opposite side of the longitudinal bore and adapted to engage the headed element and 45 provided with a recess to enter a circumscribing groove of the inner member and embrace three sides thereof.

In testimony whereof I affix my signature.
ALBERT H. NEE. [L. S.]
